UNITED STATES PATENT OFFICE.

JOHN NEUMANN, OF CHICAGO, ILLINOIS.

SEALING-WASHER FOR JARS.

Specification of Letters Patent. Patented Feb. 13, 1917.

1,215,399.

Application filed April 5, 1916. Serial No. 89,022.

To all whom it may concern:

Be it known that I, JOHN NEUMANN, a citizen of the United States, residing at Chicago, in the county of Cook and State of Illinois, have invented certain new and useful Improvements in Sealing-Washers for Jars, of which the following is a specification.

My invention relates to improvements in sealing devices for jars, bottles, or the like.

Heretofore glass preserve and fruit jars and similar receptacles have been sealed by fitting a band or ring usually known as a washer and formed of rubber or similar elastic material, around the jar neck and against the bead or flange formed thereon and compressing it upon the same by a screw or spring pressed cap.

The principal disadvantages of this construction are that the washer is constructed of material (rubber) which is comparatively short lived, is quite costly and expensive to manufacture, is easily rotted by the contaminating acids in the jar and in a number of cases fails to produce an air and liquid tight seal.

My improved device is designed to avoid these disadvantages and to this end I construct my washer of strong paper such as certain kinds of straw and pulp board and dip or immerse the washer in a molten mass of hot wax which penetrates the outer fiber and fills the interstices and when cold forms a thick coating or covering which is squeezed in place between the jar neck, bead and cap, forming a perfect air and water tight seal.

The objects of my invention are to produce a durable and long lived washer of very inexpensive material, and exceedingly cheap to manufacture, which cannot be injured or rotted by acids or other materials, and which when in position will form a perfect seal.

These and other objects I accomplish as hereinafter set forth in the following description and as particularly pointed out in the appended claims, reference being had to the accompanying drawings in which two embodiments of my invention are shown.

Figure 1, is a view of another form of my improved washer partially in edge elevation and partially in section.

Fig. 2, is a fragmentary section through a jar with a transverse section through the form of washer shown in Fig. 1, and fitted

in place upon the jar, the top cap being omitted.

Fig. 3, is a top plan of the form of my improved washer shown in Fig. 1.

In referring to the forms of my invention shown in the accompanying drawings in detail, like numerals designate corresponding parts.

In the washer shown in the drawings, the body 8, is made hollow, being practically U-shaped in cross section and the sides thereof are corrugated as shown at 9, in Figs. 2 and 3, to stiffen and strengthen the construction and also provide annular grooves which can be filled with wax forming exterior wax rings 10 upon the sides of the washer.

The interior of the washer is also filled with wax as shown at 11 in Figs. 2 and 3.

Referring to Fig. 3, it will be noted that the U-shaped form of my improved washer opens interiorly or toward the surface of the bottle neck around which it is fitted so that when the top cap is pressed down upon the washer it flattens the same and squeezes the interior wax filling 11 inwardly.

This causes the wax to fill all the small crevices and interstices and forms a perfect air and water tight seal which cannot deteriorate or rot with age, or from contact with acids and is therefore of a permanent and lasting character.

It should be noted that a portion of the hot liquid wax is absorbed into the surface of the paper inseparably combining with it and forming a composite paper and waxen surface.

While the exterior portions of the wax not intimately associated with the paper surface can be moved quite easily by pressure the composite surface is quite strong and is practically anchored to the paper.

While I have illustrated and described a preferred form of construction for carrying my invention into effect, the same is capable of a wide range of variation, alteration, modification and change without departing from the spirit of the invention, I therefore do not wish to be limited to the construction herein shown and described, but desire to avail myself of all such variations, alterations, modifications and changes as fairly fall within the scope of the appended claims or may be construed to come within the same.

While I have specified paper particularly

as the material of which the washer is to be made, it should be understood that if desired that any soft flexible material of a fibrous character such as hemp may be employed.

What I claim as my invention and desire to secure by Letters Patent is:—

1. An annular sealing washer, having an annular groove in the face thereof and a waxy material in said groove.
2. An annular hollow sealing washer sub-

stantially U-shaped in cross section, and a wax substance in the hollow portion of the washer of a consistency capable of being squeezed out by the application of pressure 15 to the washer.

3. An annular hollow sealing washer, substantially U-shaped in cross section and having annular grooves in its side portions.

In testimony whereof I have affixed my 20 signature.

JOHN NEUMANN.
